UNITED STATES PATENT OFFICE.

JOHN N. SCHILLING, OF COLUMBUS, OHIO.

MAIL-BOX.

1,256,044.

Specification of Letters Patent. Patented Feb. 12, 1918.

Application filed February 21, 1916. Serial No. 79,512.

To all whom it may concern:

Be it known that I, JOHN N. SCHILLING, a citizen of the United States, residing at Columbus, in the county of Franklin and State of Ohio, have invented certain new and useful Improvements in Mail-Boxes, of which the following is a specification.

This invention relates to mail boxes and is designed particularly for use in cities and villages where letters, as well as newspapers and parcel post packages may be deposited.

The main object of my invention resides in the provision of a structure of guard mechanism through which the mail is deposited which is in itself burglar proof and at the same time is very rigid in construction, so that when once the box is placed for public use, the likelihood of its becoming broken or deranged will be reduced to a minimum. My guard structure comprises an entrance door and a receptacle member so connected with each other that as the door is opened, the reception member is swung to a receptive position and when the door is closed, this reception member is inverted. In its inverted position, it not only deposits the package within the box, but also lies in such position that the mail cannot be removed by the insertion of a wire or string.

Still a further object of my invention resides in a novel type of mail bag support, whereby the bag and its support may be withdrawn horizontally from the interior of the box and supported in a substantially rigid position when either in its extended or retracted position.

The preferred embodiment of my invention is shown in the accompanying sheets of drawings, in which similar characters of reference designate corresponding parts, and in which:

Figure 1 is a front elevation of the major portion of my improved letter box.

Fig. 2 is a transverse section of the structure shown in Fig. 1,

Fig. 3 is a transverse section of the lower half of my mail box showing the mail bag in extended position in solid lines and in retracted position in dotted lines,

Fig. 4 is a partial plan view of the mail bag and its supporting structure shown detached,

Fig. 5 is a fragmentary perspective show-

ing the manner of supporting the bag on its holder,

Fig. 6 is a section taken on line 6—6 of Fig. 2,

Fig. 7 is a section taken on line 7—7 of Fig. 6,

Fig. 8 is a section taken on line 8—8 of Fig. 6, and,

Fig. 9 is an enlarged cross section through the bag support showing the sliding connection between this bag support and the box casing.

In the several views there is shown a main casing 1 which is provided with an arched top such as is shown at 2 and a pair of hinged doors 3, which close the lower portion of the casing as a whole and which may be held in locked position by means of the structure shown at 4. A hinged door is provided, such as is shown at 5, through which the letter mail may be dropped and in addition to this, there is provided an arcuate door 6 through which the larger packages may be dropped. This arcuate door conforms in external shape to the arched top as is shown and is provided with a pair of radially arranged sides 7. To each of these sides there is rigidly attached a segmental gear 8 which gears are of a size slightly smaller than the ends of the arms 7, so that these arms overlap the gear teeth as is shown in both Figs. 2 and 8. These gears are mounted on stub shafts shown at 9 which latter are rotatably supported in bearing members 10 supported on the outside of the casing 1. These segmental gears are designed to mesh with complementary gears 11, these latter being rigidly secured to the reception member which has been designated 12. Referring to Figs. 6 and 8, it will be noted that these gears 11 are socketed as is shown at 13 and are further provided with an entrance slot 14. This arrangement is provided to securely fit over the bearing member 15, which latter is secured to the casing wall as is shown in Fig. 6 and each bearing member has an open top 16 into which the axle 17 may fit. The entrance slot 14 is provided so that the gear 11 may be conveniently placed in position and after the parts are assembled, it is impossible for this gear to become dislodged even should the pins securing it to the reception member, become broken. Further,

by means of the overlapping of the arms 7 of the door 6, the two gears will be prevented from getting out of mesh laterally, should either one of them become disconnected from its respective operating member. Thus, it will appear that after the parts are once assembled, there is little likelihood of them becoming dislodged and even should they become broken or disconnected, it will not be possible for them to lodge themselves in such manner as to render the operation of the box impossible. This reception member is also provided with a false bottom as is shown at 18 to decrease the concavity of this member to a desirable degree. I have made it so, so that when the guard door 6 is again lowered, it will not be necessary to elevate the package to a considerable extent before it is dumped, the center of the package itself by this arrangement remaining substantially at the pivot point of the reception member during its turning discharging movement. Further, both the reception member and the door 6 are provided with counter weights 19 and 20, which serve the purpose of automatically returning the door 6 to its closed position. Reference to Fig. 2 will show particularly that the rear of the casing is provided with a guard plate 21 curved to be concentric with the movement of the reception member to prevent the articles from clogging the passage and also the water shed shown at 22 serves a similar purpose. This water shed also prevents the use of a wire or string in removing the packages after they have been mailed and in addition to this, is inclined downwardly and outwardly to shed all rain or moisture which may be deposited upon it.

In the lower portion of the casing, I have shown a bag 23, which bag is preferably divided into two compartments 24 and 25 by the partition 26. The compartment 24 is designed to receive the parcel post or larger packages, while the compartment 25 is designed to receive the letter mail and consequently the normal arrangement of these compartments is directly beneath the discharge points for the respective classes of mail. This bag is detachably supported upon a main rectangular framework 27 by means of pins 28 and eyelets 29. In addition, this rectangular framework is mounted to slide in a horizontal plane within the casing by means of the roller 30 carried on the upper end of a bracket 31, two of these brackets being provided, one on each rear corner of the rectangular framework 27. These rollers 30 slide in guide-ways 32 mounted on the inside faces of the casing side walls as is shown. In order to firmly support the frame work and consequently the bag 23 in its proper position, I have also pivotally mounted a reach rod 33 on each

side of the framework 27 as is shown at 34. These reach rods are of such length that they will stand in substantially vertical position when the bag is in retracted position as is shown in dotted outline in Fig. 3 so that the lower end of the reach rods rest upon the floor of the casing. In this manner the frame-work has four points of support, the two rollers 30 and the ends of the two reach rods 33. However, to also firmly support the rectangular framework in a horizontal position when it is in extended position as is shown in full lines in Fig. 3, I have notched the lower ends of the reach rods as is shown at 35 and these notches are designed to coöperate with brackets 36 after the manner shown in Fig. 3. The extent to which the framework is moved outwardly, governs which notch 35 is to coact with the bracket 36 and it will be noted that these reach rods lie in an inclined position so that they automatically drop into the proper notch by gravity. When it is desired to retract the framework, the reach rods are slightly elevated and the structure as a whole then pushed rearwardly in the guide channels 32. The bracket is also so shaped that in the return movement by elevation of the rods 33, these rods will not be removed from their proper position because of engagement with the opposite legs of the bracket 36.

From the foregoing description, taken in connection with the accompanying sheets of drawings, it will be noted that I have provided a mail box which is practically burglar proof and at the same time, it is very convenient of operation, this especially in connection with parcel post packages. The device is also so constructed that the parts are all rigidly held in position to reduce breakage to a minimum. In addition to this, a convenient structure has been provided for moving the receiving bag between operative and inoperative positions.

What I claim, is:

1. A mail box comprising a casing, a door structure through which the mail is inserted, a bag into which the mail may be dropped, a rectangular frame on which said bag is supported, a guideway on the inside of the casing, means whereby the rear end of said frame slidably engages said guideway, a bracket carried by the inside of said casing beneath said guideway, and a reach rod pivotally attached at one end to said frame and provided with a series of notches adjacent its other end designed to coöperate with said bracket to support the frame in extended position.

2. A mail box comprising a casing, a door structure through which the mail is inserted, a bag into which the mail may be dropped, a rectangular frame on which said bag is

supported, a guideway on the inside of the casing, means whereby the rear end of said frame slidably engages said guideway, a bracket carried by the inside of said casing beneath said guideway, and a reach rod pivotally attached at one end to said frame and provided with a series of notches adjacent its other end designed to coöperate with said bracket to support the frame in extended position, said rod being of a length

so that its notched end will rest on the mail box floor to support the frame in retracted position.

In testimony whereof I affix my signature in presence of two witnesses.

JOHN N. SCHILLING.
